UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR.

Application filed February 15, 1924. Serial No. 693,120.

To all whom it may concern:

Be it known that I, FRED D. HOLDSWORTH, a citizen of the United States, residing at Claremont, in the county of Sullivan and 5 State of New Hampshire, have invented certain new and useful Improvements in Compressors, of which the following is a full, clear, and exact specification.

My invention relates to compressors, and 10 particularly to rotary compressors.

An object of my invention is to provide an improved compressor. Another object of my invention is to provide an improved rotary compressor. A further object of my 15 invention is to provide an improved rotary compressor which while it is adapted to compress air to a considerable pressure will yet operate efficiently when compressing to lower pressures. A still further object of 20 my invention is to provide an improved compressor of the rotary type which, although designed to compress to a substantial pressure, will not be wasteful of power during the building up of its designed pressure in 25 the receiver or discharge line. Other objects and advantages of my invention will herein-after more fully appear.

In the accompanying drawings I have shown for purposes of illustration one form 30 which my invention may assume in practice.

In these drawings,—

Fig. 1 is a plan view, with parts broken away of an illustrative embodiment of my invention.

Fig. 2 is a transverse vertical section on 35 a plane corresponding to line 2—2 of Fig. 1.

Fig. 3 is a detail fragmentary sectional view on a plane corresponding to line 3—3 of Fig. 1.

40 In the illustrative embodiment of my invention I have shown the same comprising a casing consisting herein of three main parts, a central rotor housing 1 and heads 2 and 3. Within the rotor housing there are

45 formed a pair of intersecting bores 4 and 5 which form rotor chambers and the rib between these is cut away below to form a bottom 6 through which opens a passage 7 which may be supplied with air through

50 either or both the pipes 8 and 9. Within the rotor chambers there are a pair of rotors 11 and 12, which rotors may be formed if desired as in the patent to Leonard, 1,188,286, or each in the form of a pair of such spiral

55 elements with an intermediate spur gear ele-

ment, these rotors being thereby provided with intermeshing tooth blades forming pockets within which the fluid may be compressed and these rotors are keyed or otherwise held on shafts 13 and 14. The shaft 60 13 is journaled in a suitable manner in the opposite heads, the mode of journaling not being shown as it is not material to my invention; while the shaft 14 is provided with an extension 15 and is suitably journaled at 65 its opposite ends by means not shown, the extension carrying a gear 16 which is driven by an internal gear 17 on a shaft 18, while the shaft 18 carries a driving pulley for the compressor. The speed multiplying gearing 70 increases the output of the compressor.

Above the rotor chambers and formed in the upper part of the casing 1 is a chamber 20 and connecting this chamber with the rotor chambers is a series of ports. One of 75 these ports 21 is arranged midway between the rotors and also midway of the length thereof and this is the final discharge passage for fluid. At opposite sides of the passage 21 there are arranged passages respectively designated 22, 23, 24 and 25, these 80 passages not being spaced a great distance from the passage 21. Additional passages 26, 27, 28 and 29 also traverse the casing and open into the rotor chamber, these supplemental passages being located nearer the 85 ends of the rotors and also farther from the mesh line of the rotors. The purpose of these several passages is to provide for discharge of the compressed fluid at different 90 times, it being apparent that the pockets containing fluid in process of being compressed will come into communication with the ports 26, 27, 28 and 29 before they will communicate with the ports 22, 23, 24 and 95 25, and that the pockets will come into communication with this last mentioned series 100 of ports earlier than they will communicate with the central discharge port 21. The several passages 21 to 29 open through a valve seat surface, this surface herein being designated 30 and being in the shape of an X at the intersection of whose arms the passage 21 is disposed and in whose arms the other 105 passages also terminate. At the ends of the arms there are provided guiding shoulders 31, 32, 33 and 34 and these serve to maintain in position an annular valve 35. Mounted in each one of the arms of the X adjacent 110 the central opening 21 is a pin, these several

pins being indicated herein by the same numeral, namely, 37. These pins at their outer sides guide a second valve member 38 while with their inner edges they guide a third, 8 round, valve member 39. It will be noted that the valve member 35 controls the ports 26, 27, 28 and 29, the annular valve 38 controls the passages 22, 23, 24 and 25, and the circular valve 39 controls the passage 21. It 10 will be observed that a guard plate 40 is held by machine screws 41 in spaced relation to the valve seat and serves to prevent the lifting of the valves to an excessive height above their seats. Suitable cooling jacket 15 means 42 is provided for the compressor.

The operation of this device will be readily apparent. It will be understood that if the receiver or discharge line to which the compressor is designed to pump air is initially filled with fluid only at atmospheric pressure, the tooth pockets, were they to compress the fluid trapped in them until they open into communication with the passage 21, would do a substantial amount of unnecessary work and would compress the fluid to a substantial pressure and this work would be lost on release of the fluid compressed into the receiver or discharge line. Accordingly, on starting up of the compressor, after only a small amount of compression, the air within the tooth pockets will be brought into communication with the ports 26, 27, 28 and 29 and if the pressure within the pockets is substantially greater than that in the valve chest 20 the excess pressure will then be discharged and as further compression occurs there will be successive discharges through the ports 22, 23, 24 and 25, and the port 21. As the pressure in the receiver or discharge line goes up to a higher and higher degree, it will be evident that the air compressed within the tooth pockets will not be under sufficient pressure when the ports 26, 27, 28 and 29 are reached to unseat the valve 35, but in case the pressure in the valve chest is substantially below the desired maximum, it may be that the valve 38 will be unseated when the chambers or pockets come into communication with the chambers 22, 23, 24 and 25. As the pressure builds up to a still higher amount, however, this valve also will cease to open and the pressure will finally be discharged only through the port 21. It will accordingly be evident that I have provided an arrangement which will permit thoroughly efficient operation in the matter of the avoidance of over-compression, but which will nonetheless permit the compressor to operate effectively when the discharge pressure is the maximum desired and which will, moreover, permit efficient operation with constant discharge line pressure below the maximum.

While I have in this application specifically described one form which my inven-

tion may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rotary compressor, means forming 75 a casing having intercommunicating rotor chambers, rotors in said chambers having spirally disposed intermeshing tooth blades forming with the walls of said chambers compression pockets, and means for discharging compressed fluid including ports communicating with said chambers at different distances from the mesh line of said rotors.

2. In a rotary compressor, means forming 85 a casing having intercommunicating rotor chambers, rotors in said chambers having spirally disposed intermeshing tooth blades forming with the walls of said chambers compression pockets, and means for discharging compressed fluid including ports communicating with said chambers at different distances from the median transverse plane of said rotors.

3. In a rotary compressor, means forming 95 a casing having intercommunicating rotor chambers, rotors in said chambers having spirally disposed intermeshing tooth blades forming with the walls of said chambers compression pockets, and means for discharging compressed fluid including ports communicating with said chambers at different distances both from the mesh line of the rotors and from the median transverse plane of said rotors.

4. In a rotary compressor, means forming 100 a casing having intercommunicating rotor chambers, rotors in said chambers having spirally disposed intermeshing tooth blades forming with the walls of said chambers compression pockets, and valved means for discharging compressed fluid including ports communicating with said chambers at different distances from the mesh line of said rotors.

5. In a rotary compressor, means forming 110 a casing having intercommunicating rotor chambers, rotors in said chambers having spirally disposed intermeshing tooth blades forming with the walls of said chambers compression pockets, and valved means for discharging compressed fluid including ports communicating with said chambers at different distances from the median transverse plane of said rotors.

6. In a rotary compressor, means forming 120 a casing having intercommunicating rotor chambers, rotors in said chambers having spirally disposed intermeshing tooth blades forming with the walls of said chambers

- compression pockets, and valved means for discharging compressed fluid including ports communicating with said chamber at different distances both from said mesh line and 5 from the median transverse plane of said rotors.
7. In a compressor, means forming a housing providing intercommunicating rotor chambers, rotors therein having intermeshing spirally disposed tooth blades, means for rotating said rotors so that said tooth blades form pockets of diminishing area as rotation takes place, port means communicating with said chambers such that 10 said pockets will communicate therewith at different periods, and separate valve means for the port means communicated with by said pockets at different times.
8. In a rotary compressor, means forming 20 a casing having intercommunicating rotor chambers, rotors in said chambers having spirally disposed intermeshing tooth blades forming with the walls of said chambers compression pockets, and means for discharging compressed fluid including ports communicating with said chambers at different distances from the mesh line of said rotors, and common valves for such of said ports as are disposed at equal distances from 25 said mesh line.
9. In a rotary compressor, means forming a casing having intercommunicating rotor chambers, rotors in said chambers having spirally disposed intermeshing tooth blades 30 forming with the walls of said chambers compression pockets, and means for discharging compressed fluid including ports communicating with said chambers at different distances from the mesh line of said rotors, and common automatically actuated valves for such of said ports as are disposed at equal distances from said mesh line.
10. In a rotary compressor, means forming 40 a casing having intercommunicating rotor chambers, rotors in said chambers having spirally disposed intermeshing tooth blades forming with the walls of said chambers compression pockets, and means for discharging compressed fluid including ports 45 communicating with said chambers at different distances from the mesh line of said rotors, and common valves for controlling ports at equal distances from said median transverse plane.
11. In a rotary compressor, means forming 50 a casing having intercommunicating rotor chambers, rotors in said chambers having spirally disposed intermeshing tooth blades forming with the walls of said chambers compression pockets, and means for discharging compressed fluid including ports 55 communicating with said chambers at different distances from the median transverse plane of said rotors, and common annular valves for controlling the discharge of fluid 60 through the ports arranged at equal distances from the median transverse plane of the rotors.
12. In a rotary compressor, means forming 65 a casing having intercommunicating rotor chambers, rotors in said chambers having spirally disposed intermeshing tooth blades forming with the walls of said chambers compression pockets, and means for discharging compressed fluid including ports 70 communicating with said chambers at different distances both from the mesh line of the rotors and from the median transverse plane of said rotors, and annular valves each of which controls all the ports at a given distance from the intersection of the vertical plane including the mesh line of the rotors and the median transverse plane of the rotors.
13. In combination, in a compressor, a 75 casing having intercommunicating rotor chambers, rotors therein having intermeshing spiral tooth blades forming longitudinally contracting compression pockets, and discharge means communicable with said compression pockets when the extremities of 80 said pockets are at different angular positions.
14. In combination, in a compressor, a 85 casing having intercommunicating rotor chambers, rotors therein having intermeshing spiral tooth blades forming longitudinally contracting compression pockets, and discharge means operative to permit discharge of fluid from said pockets whenever 90 the pressure therein exceeds the pressure in the discharge line by a certain small amount.
15. In a rotary compressor, a casing, intermeshing spiral-toothed rotors therein co-operating to form longitudinally contracting 100 compression pockets, and means operative to permit discharge of fluid at different pressures from said pockets.
16. In combination, a compressor casing 105 having intercommunicating rotor chambers, cooperating rotors therein rotatable on axes always relatively fixed, and discharge means communicable with said rotors at different angularly related positions.
17. In combination, a casing having intercommunicating rotor chambers and cooperating compressor rotors disposed therein, inlet and discharge passages communicating therewith, and valvular means cooperating 115 with said rotors independently of said inlet passage to control the pressure of the fluid compressed by said rotors.
18. In combination, a casing having intercommunicating rotor chambers, cooperating 120 compressor rotors disposed therein, and valve controlled means cooperating with the periphery thereof to control the pressure to which fluid is compressed by said rotors.
19. In combination, a casing having intercommunicating rotor chambers, cooperating 125

compressor rotors disposed therein, and valve controlled means cooperating with the periphery thereof to control the pressure to which fluid is compressed by said rotors, 5 said valvular means comprising a plurality of valves made successively inoperative as the pressure of the fluid compressed by said rotors increases.

20. In combination, a casing having cooperating compressor rotors and an outlet passage, discharge passages communicating with said outlet passage and the rotor peripheries, and valves for controlling said discharge passage adapted to be successively 15 inoperative in accordance with the degree of pressure in said outlet passage.

21. In combination, fluid compressing mechanism, an outlet passage, discharge passages communicating with said compressing 20 mechanism and outlet passage, and a plurality of valves made successively operative to close certain of said discharge passages automatically in accordance with the pressure in the outlet passage.

25. 22. In combination, fluid compressing mechanism, an outlet passage, discharge passages communicating with said compressing

mechanism and outlet passage, a plurality of valves made successively operative to close certain of said discharge passages automatically in accordance with the pressure in the outlet passage, and means whereby fluid flow through one of said discharge passages may be had during the closure of the other passages. 30 35

23. In combination with a compressor having an outlet passage, of a plurality of discharge passages allowing communication between said compressor and outlet passage, and means for closing certain of said discharge passages in accordance with the pressure in said outlet passage while allowing fluid flow through the remainder of said passages. 40

24. In combination, a compressor casing 45 enclosing cooperating compressor rotors, and means cooperating with the periphery of said rotors and always having a longitudinally fixed relation thereto for controlling the degree of pressure to which fluid is compressed by said rotors. 50

In testimony whereof I affix my signature.

FRED D. HOLDSWORTH.
